Primary Examiner — Angela J Lee(74) *Attorney, Agent, or Firm* — Sughrue Mion, PLLC(57) **CLAIM**

The ornamental design for a USB memory, as shown and described.

DESCRIPTION

FIG. 1 is a perspective view of USB Memory showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view showing the USB Memory in an open position.

The broken lines are for environmental purposes only and form no part of the claimed design.
